United States Patent Office.

FRANKLIN FIELD, OF TROY, NEW YORK.

Design No. 3,870, dated March 1, 1870.

DESIGN FOR A COLLAR AND CUFF BOX.

The Schedule referred to in these Letters Patent and making part of the same.

To all whom it may concern:

Be it known that I, FRANKLIN FIELD, of the city of Troy, in the county of Rensselaer, and State of New York, have invented and produced a new and original Design for Boxes used for Packing Collars and Cuffs, of which the following is a specification.

The nature of my design is fully represented in the accompanying drawings, to which reference is hereby made.

Figure 1 represents the box when closed, and

Figure 2 as it appears when partially open.

The box is made of paper, cloth and paper, or other suitable material, and the lower part or body thereof is made in a square form, as shown in the drawings. This body or main portion of the box is provided with a lid or cover, which is of a depth at its front side equal to the depth of the box, but which is cut away on each side, so that the sides of the lid or cover are of triangular shape, the lower edges thereof slanting

from the bottom of the front side to the top of the rear side of the box when closed, as shown in fig. 1.

This lid or cover is capable of being swung open when desired, to permit the collars or cuffs packed therein to be taken out and replaced at pleasure.

The object of my design is to make the box from which collars and cuffs, and especially paper collars and cuffs are sold, a neat and tasteful piece of toilet furniture, as well as a convenient receptacle for the articles therein contained.

I claim as my invention the design for a packing-box for collars and cuffs, as shown and specified.

In witness whereof I have hereunto set my hand this 8th day of February, 1870.

F. FIELD.
